UNITED STATES PATENT OFFICE

1,930,012

WATER CLOSET

Olof Lundberg, Saltsjobaden, Sweden

Application November 20, 1930, Serial No. 497,043,
and in Sweden November 23, 1929

3 Claims. (Cl. 4—14)

This invention relates to a water closet with flushing cistern made in one aggregate. It has been a general desire not to have the water closets made in different parts, namely the water closet bowl standing on the floor, and the flush tank secured on the wall above the bowl and connected with the latter by a pipe, as it has been most usual hitherto, but it is preferred to have the water closets made in one aggregate which 10 may be placed independently in the closet-room or the bathing-room. The requirements on such a water closet aggregate are amongst other the following.

The connection between the water closet bowl 15 and the flushing cistern must be simple and practical, so that a durable and leakage-free connection is obtained without inconvenient boltings and closure devices.

Sufficient large channels must be present between the flushing cistern and the closet bowl, so 20 that the flushing water may rapidly and effectively be discharged into the bowl in order to flush the same effectively.

The flushing water must be lead in such a manner that it flushes the entire inner wall surface 25 of the bowl.

The device for effecting the flushing must be convenient and reliable.

All these requirements are fulfilled in a water 30 closet according to this invention.

As an example, a water closet according to this invention is shown in the accompanying drawings, wherein

Fig. 1 is a vertical longitudinal section of the 35 water closet having all the parts in initial position,

Fig. 2 shows the upper part of the closet in vertical longitudinal section with the seat lid raised and the valve flaps of the flushing cistern closed, 40 the tap being made free to function,

Fig. 3 is a transverse vertical section on the line A—A of Fig. 1,

Fig. 4 is a horizontal section on the line B—B of Fig. 1,

45 Figs. 5 and 6 show on a larger scale a detail of the movement transfer mechanism between the seat lid and the valves of the flushing cistern, Fig. 5 being a vertical section on the line C—C of Fig. 6 and Fig. 6 being a horizontal section on the line D—D of Fig. 5.

In the upper part of the water closet 1 there is a flushing cistern chamber 2 the bottom of which is situated somewhat beneath the upper edge 4 of the bowl 3. In the chamber 2 a flushing cistern 5 is partly sunk. The flushing cistern

5 is provided with a resting surface 6 resting on the upper edge of the flushing cistern chamber, said upper edge being situated in the same horizontal plane as the upper edge 7 of the water closet. The lower part 8 of the flushing cistern 60 then extends down into the flushing cistern chamber 2, while the upper part 9 of the flushing cistern projects a distance above the upper edge 5 of the closet bowl. That wall of the lower part 8 of the flushing cistern which is turned towards the bowl 3, is provided with one or more (according to the drawings three) discharge-holes 10 at which clack valves 11 are arranged.

A vertical channel 12 extending through the flushing cistern chamber 2 and being open at 70 both ends, is formed of the faience, and a vertical pipe 13 is watertightly secured to the bottom of the flushing cistern 5, the lower end of said pipe being situated beneath the bottom of the flushing cistern chamber 2. The flushing cistern 5 is 75 locked to the closet by a nut 14 of the pipe 13, and closure at the hole of the bottom of the flushing cistern chamber is obtained by a usual tightening ring. The pipe 13 forms a channel open at both ends which channel extends upwards to the upper part 9 of the flushing cistern and opens above the water-level in the cistern when the latter has been filled with flushing water.

A segment 17 is attached to the seat lid 16. A 80 rope 30 secured to the lid runs over the segment, down through the channel 12, round guiding-wheels 18 the supporting member of which is bolted to the bottom of the flushing cistern chamber, upwards through the pipe 13 and round the 85 wheel 19 to which the rope is secured and the supporting member of which is attached to the upper part of the pipe 13. Then the rope extends down to a cross-piece 20 to which the rope is adjustably fixed. As will be seen from Fig. 3 the 90 cross-piece 20 is provided with three plates 21 adjustable vertically in relation to the cross-piece. The clack valves 11 are by chains connected to said plates. Owing to this arrangement 95 the clack valves may be adjusted in such a way, that one valve will first be opened and then the two other ones, or inversely, when the flushing is to take place.

As will be seen from Figs. 5 and 6, the wheel 19 is rotatably mounted on a horizontal shaft 100 22 and provided with a lateral pin 23 adapted to actuate a lever 24 mounted to swing vertically on the supporting member of the wheel 19. In the initial position according to Figs. 1 and 3 a lever 26 of a float operated tap 25 rests on the lever 110

24. The float 27 is secured to the lever 26 so as to be able to be raised and lowered. Guiding walls 28 (Fig. 4) are formed of the faience, and an overflow pipe 29 is watertightly secured to 5 the bottom of the flushing cistern.

When the closet is to be used the seat lid 16 is raised from the initial position (Fig. 1) to the position shown in Fig. 2. The segment 17 will then be swung downwards, whereby the rope 30 10 is slackened and the cross-piece 20 together with the valve flaps 11 connected thereto are lowered owing to their weight, so that the valve flaps will close the discharge-holes 10. As the rope 30 is secured to the wheel 19 the latter will be rotated with the sun, when the cross-piece 20 and 15 the valve flaps are sunk. The pin 23 will be raised, so that the lever 24 is liberated. The lever 26 of the tap which lever rests on the lever 24, will then be lowered owing to the weight of the 20 float, whereby the tap 25 will be actuated in such a manner, that the tap is opened and the water streams into the flushing cistern. When the water level in the flushing cistern has raised to the desired height the float rises.

25. The height position of the float has been adjusted in such a way that the float will then float on the water. At the same time as the float the lever 26 attached thereto also raises and the tap 30 is closed. The desired flushing water quantity 35 is now in the flushing cistern and the different parts have the position shown in Fig. 2.

When the closet has been used the seat lid 16 is laid down. Thereby the segment 17 will be swung upwards and causes a pull in the rope 30, so that the valve flaps 11 are raised liberating 35 the discharge-holes 10. The flushing water collected in the flushing cistern will now stream through the discharge-holes into the bowl 3. The water is led by the guiding walls 28 (Fig. 40 4) in such a way, that the entire inner surface of the bowl will be effectively flushed. As the rope 30 is secured to the wheel 19 the latter is rotated contrary to the sun, when the seat lid 45 is laid down. The pin 23 will then be lowered and acts upon the lever 24, so that the latter again occupies the position shown in Fig. 1 and 50 supports the float lever 26, so that the tap is held closed. In this position the lever 24 serves as a locking device for the float lever. As the clack valves by means of the plates 21 may be adjusted in such a way that they will be opened at different moments, the flushing water is caused to stream first to one part of the bowl and then to another part of the same.

55. If for some reason the water level in the flush-

ing cistern should raise above the normal height, the excess of water flows through the overflow pipe 29 into the bowl. As the upper end of the overflow pipe is situated lower than the upper end of the pipe 13, no water can flow down through the pipe 13 and cause leakage on the floor.

80 Water closets arranged according to this invention may be made in many other ways than that described as an example, without departing from the spirit and scope of the invention. For instance the device for transmitting the movement of the seat lid to the clack valves and to the locking lever 24 for the float operated tap may 85 comprise levers or the like.

90 Having now described my invention, what I claim as new and desire to secure by Letters Patent is:

1. In combination, a closet bowl, a chamber located substantially at the level of the bowl forming a part thereof and being in open communication therewith, a stationary flush tank wholly supported by said chamber and extending into the latter, a shoulder on said flush tank bearing on said chamber, and a discharge valve 100 provided in said flush tank.

2. An arrangement as claimed in claim 1, characterized by the provision of means establishing permanent communication between the flush tank and the atmosphere a lid member for 105 the bowl, a discharge valve for the flush tank, means connecting the lid with the discharge valve, a water supply valve controlled by said connecting means, said connecting means operating, when the lid is lifted into its uppermost position, to close the discharge valve and open the water supply valve and, when the lid is closed, to open the discharge valve.

3. An arrangement as claimed in claim 1, characterized by the provision of means establishing permanent communication between the flush tank and the atmosphere a lid member for the bowl, a discharge valve for the flush tank, means connecting the lid with the discharge valve, a water supply valve controlled by said connecting 115 means, said connecting means operating, when the lid is lifted into its uppermost position, to close the discharge valve and open the water supply valve and, when the lid is closed, to open the discharge valve, and fluid-tight guides extending through said chamber and the flush tank and receiving said connecting means, the guide in the flush tank extending above the level of the water therein when the flush tank is filled.

120 125 130 OLOF LUNDBERG. 135
